(57) CLAIM

We claim the ornamental design for a package for a dough product, as shown and described.

DESCRIPTION

FIG. 1 is a perspective view of a first embodiment of a package for a dough product showing our new design;

FIG. 2 is a front view thereof;

FIG. 3 is a top view thereof;

FIG. 4 is a bottom view thereof; and

FIG. 5 is a side view thereof;

FIG. 6 is a perspective view of a second embodiment of a package for dough product;

FIG. 7 is a front view thereof;

FIG. 8 is a top view thereof;

FIG. 9 is a bottom view thereof; and,

FIG. 10 is a side view thereof.
